Application June 12, 1928. Serial No. 284,767

9 Claims. (Cl. 234—56)

This invention relates to improvements in time recording devices and more particularly to improvements in time stamps.

One of the objects of the invention is to provide a printing mechanism which may be readily removed for inspection or replacement independent of the motor mechanism for driving said printing mechanism.

Another object is to provide new and improved means for removing the casing enclosing the printing mechanism to render said mechanism accessible for inspection without interrupting the operation of the same.

Still another object is to provide an improved construction for a printing head type time stamp whereby the arm carrying the printing and motor mechanisms may be removed from the base without disturbing the restoring spring for the arm.

A further object is to provide a new and improved connection between the arm and the spring which restores it.

A still further object is to provide improved means for manually setting the type wheels without disconnecting the driving mechanism therefrom.

A still further object is to provide an improved and novel construction for manually setting the type wheels in the train.

Still another object is to provide means to enable said stamp to be operated in conjunction with an electrical system of the self regulating type whereby said stamp will be corrected periodically should it get out of synchronism with other units on the same system.

Other objects and advantages of this invention will be apparent from the specifications and the accompanying drawings which show one embodiment of this invention and wherein similar reference numerals indicate similar parts and 40 wherein, in the drawings:

Fig. 1 shows side elevation of stamp;

Fig. 2 is a detail of record printed by stamp;

Fig. 3 is a detail showing the method of mounting the printing head on the arm;

Fig. 4 is a longitudinal section through the time stamp;

Fig. 4a is a detailed view of the spring anchor;

Fig. 5 is a section on line 5—5 of Fig. 4;

Fig. 6 is a section on line 6—6 of Fig. 4;

Fig. 7 is a left side elevation of head with cover plate cut away;

Fig. 8 is a right side elevation of head with cover plate cut away;

Fig. 9 is a section through lines 9—9 of Fig. 4;

Fig. 10 is a section through lines 10—10 of Fig. 4;

Fig. 11 is a detail of transfer gears;

Fig. 12 is a plan view of Fig. 11;

Fig. 13 is a detail of impositive stops on day 60 wheel and month wheel shafts shown looking from lines 11—11 of Fig. 6;

Fig. 14 is a wiring diagram showing method of operating type wheel.

This time stamp is of a class commonly known 65 as a printing head type time stamp and may comprise a base 20 in which is mounted a platen 21 and to which is pivotally attached at 22 an arm 23 having mounted on one end thereof a printing head which is encased by two side plates 24 and 24a and a front plate 25 and to which is fixed an operating handle 26. Within the printing head are located type wheels and their associated actuating and transferring mechanisms together with an ink ribbon with its associated feeding 70 and reversing mechanism, all of which will be explained in detail later. The type wheels are advanced by timed electric impulses such as may be initiated by a master clock diagrammatically shown in Fig. 14. When an operator desires to 75 print or stamp the information designated by the type wheel within the printing head on some article, said article is placed over the platen 21 and under the printing head and the operator presses down upon the handle 26 thus moving the 80 type head downward about its pivot 22 and into contact with the article to be stamped which is supported by the platen.

The information indicated by the type wheel at the time of stamping will be printed by means 90 of said type and its coating ribbon on the said article leaving thereon a printed registration as shown in Fig. 2. When the operator releases the printing head it rises from the article just printed to a position shown in Fig. 1, by means which will 95 be explained later.

The side plate 24 (Figs. 1, 5, 7 and 8) is provided with a notched lug 27 fixed at the inside front end and a hooked member 28 fixed on the inside rear end. To mount the side plate 24 onto the 100 printing head the notched lug 27 is slid from the front into a notch 29 provided in the side supporting frame 30 one of which is provided on each side of the printing head to support the type wheels and associated mechanisms. The hooked 105 member 28 is then engaged with an annular groove around the end of the rod 31, said rod being journaled in bushings 32 mounted on the supporting frames 30 and 30a and being held from lateral movement by the hooks 28. The 110

side plates are provided with holes through which the ribbon spindles 33a and 33b may be inserted when the side frames are in position. Holes are also provided such as at 34 which are opposite 5 certain shafts to which type wheels are attached to render the ends of these shafts accessible so that they may be turned by means of a suitable key in order to manually set the type.

The front plate 25 of the casing is provided with 10 a lug 35 at each lower corner. The plate is mounted on the printing head after the side frames 24 are mounted, the lugs 35 being engaged in the notches 29 of the side supporting frames 30 and 30a. The top of the plate 25 has a hole 15 which coincides with a tapped hole in the cross piece 36 which is an integral part of the arm 23. When the front plate is placed in position, with the two holes just mentioned coinciding, the handle 26 containing a threaded stud 37 is screwed 20 down tightly onto the plate by screwing said stud into the tapped hole. This holds the front plate 25 firmly in position. The outside edges of the front plate turn down and over the upper edges of the side frames thus forming a complete housing 25 for the printing head.

A large hole with a bezel 38 fixed to the rim of said hole is provided in the plate to make visible a clock dial which coincides with said hole 38 when the first plate is in position. The usual 30 well known dial, hands, dial ring, protection glass and dial works are all mounted on and supported by a bracket 39 fastened securely to the side supporting frames 30. These are furnished as a matter of convenience for the operator to 35 be able to tell the time as well as serve as an indication of what the time stamp is about to print.

On the base 20 of the device is fixed a platen 21 of suitable resilient material and in the base is a spring 40 attached at one end to a stud 41 40 fixed to the base and attached at the other end to a flat anchor plate 42 having integral with it two hooked members 43 which coat with a stop bar 44 fixed to the base 20 (Figs. 4 and 4a). In the plate 42 are two holes 42a through which 45 project tail pieces 45 of the arm 23. The purpose of the stop bar 44 is to limit the amount which the spring 40 may act on the arm 23. Said arm is pivoted on a rod 46 journalled in the base 20 and held from lateral motion by enlarged 50 portions at each end of the rod. One of the enlarged ends being removable from the pivot rod 46 to permit the rod to be withdrawn. The action of the spring 40 on the tail pieces 45 moves the arm 23 clockwise until the hooked members 43 come in contact with the stop bar 44 so that normally the printing head is held 55 up from the printing platen 21 as illustrated in Fig. 1. When the printing head is depressed the tail pieces 45 coating with the holes in the plate 42, displace said plate to the right against the 60 tension of the spring 40 which spring returns the arm 23 and its associated printing head to its normally raised position as soon as the force causing said printing head to be depressed is 65 removed. If it is desired to remove the arm from the base for the purpose of replacement and inspection the pivot rod 46 is removed by first removing the nut 22 and then withdrawing said rod from its journals. The arm 23 may then be 70 lifted out of cooperation with the base 20 withdrawing the tail pieces 45 from the holes in the anchor plate 32 said plate remaining held in position by the hooked members 43 cooperating 75 with the fixed bar 44. This eliminates the cus-

tomy necessity of removing the cover plate from the base and disengaging the spring.

The arm 23 is hollow having a channel formed cross-section with the under side open. Mounted therein is motor drive assembly consisting of a bracket 48, a magnet 49 and an armature 50 (Fig. 4). The bracket 48 is held firmly to the arm 23 by means of two T shaped studs 51 fixed to the arm 23 and projecting through and slidably cooperating with two elongated holes 52. These holes being large enough at one end to receive the large head of the stud and smaller than said large head but of sufficient width to receive the smaller diameter of the shank of the stud 51. A screw 53 is provided, passing through the bracket 48 and engaging a threaded hole in the arm 23. The screw prevents the bracket 48 from sliding back so that the enlarged portion of the hole 52 presents itself to the stud 51 which would cause the bracket to become disengaged from the arm 23. Formed up on opposite sides of the bracket 48 and integral with it are two ears 54, one of which is not shown. These ears journal on shaft 55 about which the armature 50 pivots. 95

Also formed up on one side only and integral with the bracket 48 is a projection 56 shown dotted in Fig. 4 said projection forming a support for a lever 57 pivoted at 58. The end of the bracket 48 opposite the screw 53 is formed downwardly 105 and to this downwardly formed portion is rigidly fixed the core of the magnet 49 by means of a screw 59 passing through a hole in the bracket and engaging a threaded hole in the end of the core. Also fastened to the bracket 48 by means of screws 60 is an insulated terminal block 61 to which are fastened the wires from the multiwire cable 62 which is passed through a hole in the lower rear of the arm 23, said hole being lined with any well known type of insulating bushing 115 63 for the protection of the cable. To remove the magnet 49, the printing head is swung forward as illustrated in Fig. 3 and in a manner to be described later, the insulating block 61 is detached by removing the screws 60, the screw 53 120 is removed and the bracket 48 is moved to the right as viewed in Fig. 4 bringing the enlarged portion of the holes 52 opposite the enlarged head of the studs 51 so that the bracket 48 with the magnet 49 attached thereto may be removed from 125 the arm 23.

The printing head consists of two side supporting plates 30 and 30a and two intermediate supporting plates 79 and 80 which form the supporting structure for the printing mechanism. 130 These supporting plates are held in fixed spaced relationship to each other by the tie rods 81, fastened to the side supporting frames by the screws 82. The side supporting plates and intermediate plates will hereinafter be designated as 135 frame members.

The printing head is fixed to the end of the arm by means of slidable rods 31 and 63 which pass through holes in the frame members 30 and 30a and the arm 23 such as indicated at 64 and 140 65 respectively in Fig. 3. When the device is assembled for operation these rods are prevented from transverse movement by the side frames 24. When it is desired to replace the ribbon or casually inspect the printing mechanism the 145 housing plates 24 and 25 are removed and the rod 31 is withdrawn. The printing head is then swung forward in the position as shown in Fig. 3, which permits of such inspection. If, however, adjustments or replacements are required 150

in the mechanism, the pin 63 is withdrawn and the printing head is thereby completely detached from the printing arm. This form of construction permits the substitution of one printing head for another without disassembling the mechanism of said printing head. This is a distinct advantage inasmuch as the printing head unit is small of size and weight compared with the device as a whole and can therefore be more readily carried by a service man without inconvenience so that if a customer requires a new type arrangement or a thorough overhauling of the mechanism the service man can substitute another printing head as a relief while the necessary repairs or alterations are being made, without interrupting the customer's service or disconnecting the wiring to the machine which would be necessary if the complete device was interchanged.

20 Mounted on the arm 23 (see Fig. 3) is an insulating block 66 in which are mounted three terminal posts 67. The terminal posts are provided with insulated sleeves and extend through to the hollow portion inside of the arm 23 and there are attached to three wires the purposes of which will later be described. Fixed to the terminal posts 67 are split blades 68 which co-operate with switch blades 69 in the same manner that a switch blade cooperates with a split blade in the usual well known type of knife switch. When the printing head is swung forward in the manner indicated in Fig. 3 the switch blades 69 become disengaged from the split blades 68 and when in operating position the switch blades and split blades make contact as indicated in Fig. 7. The switch blades 69 are mounted on an insulating block 70 said block being fixed to the frame member 30. Fixed to the end of the switch blades 69 are three contact brushes 71, 72 and 73 which wipe three separate paths on the face of a gear 74 made of a suitable insulating material. On the face of the gear are mounted a contact ring 75 and two contact segments 76 and 77 which constitutes a commutator coacting with the brushes 73, 72 and 71 respectively. Contact ring 75 contacts with contact segment 76 and said contact segment contacts with contact segment 77. The gear 74 rotates on a stud 78 fixed to the frame member 30.

Operation of printing mechanism

50 Fixed to the armature 50 (Fig. 4) is an angular member 83 one leg of which rests on the head of an adjusting screw 84, mounted in a lever 85, said lever being fixed to a shaft 86 journalled in the frame members 30 and 30a (Figs. 4 and 5). Turning the adjusting screw 84 raises or lowers the coacting leg of the angular member 83 thereby moving the armature 50 about its pivot 55 thus adjusting the amount of travel the armature makes when drawn against the pole face of the magnet 49 upon energization of said magnet. When the magnet 49 is energized its armature 50 being attracted moves counterclockwise about its pivot 55 and through the member 83 attached thereto moves the lever 85, and therefore the shaft 86 clockwise as viewed in Fig. 4.

55 To one end of the shaft 86 (see also Figs. 5, 6 and 7) is fixed a lever 87 biased downwardly by a spring 88 attached at one end to an anchor post 89 fixed to said lever and attached to the frame member 30 at the other. Formed over at right angles to the lever 87 is a projection 90 which acts as a limit stop to the driving pawl 91 pivotally mounted on the lever 87 by means of a

stud 92 fixed to said lever. The pawl 91 is biased in a counterclockwise direction about its pivot by spring 93 attached to the pawl 91 at one end and to the lever 87 at the other. Said pawl has three projections indicated by reference characters 94, 95 and 96. The projection 94 coacts with the projection 90 to limit the movement of the pawl 91 in its counterclockwise rotation when said pawl is disengaged from the ratchet wheel 97. The projection 95 coacts with the ratchet wheel 97 to limit the travel of the lever 87 when it is moved downwardly to advance said ratchet wheel and also serves to cam the pawl 91 out of its normally locked position when a manual setting operation is effected as will be explained later. The projection 96 coacts with the teeth of the ratchet wheel 97 to move said wheel in a counterclockwise direction a space of one tooth each time the lever 87 is moved up and down once which constitutes one cycle of operation. This projection or pawl 96 when in its home position as shown in Fig. 7 is in the plane of the member 99a which is rigidly fixed to the plate 30 by the screws 99b and 82, said projection also abutting the edge of the member 99a. The pawl 91 also acts as an impulsive lock thus permitting the ratchet wheel 97 to be turned manually by means of a key, not shown, which fits the key receiving portion of the shaft 98 to which said ratchet wheel is fixed. When said ratchet wheel is turned in such a manner the teeth of the ratchet acting against the projection 95 cams it upward when the ratchet is moved, and as said pawl 91 is prevented from rotating due to the projection 96 resting against the ratchet wheel, the lever 87 is raised by said 100 camming action withdrawing the projection 96 from engagement with the ratchet wheel so that said wheel may rotate. A pawl 99 pivotally mounted on the stud 82 is biased against the ratchet wheel 97 by means of a spring 100. Said 105 pawl engages the teeth of said ratchet wheel to prevent the ratchet wheel from being moved in a clockwise direction.

Each time, therefore, that the magnet 49 is energized the pawl 91 is raised so that it engages 120 the next tooth on the ratchet wheel 97 adjacent to which it was previously engaged. When said magnet is next deenergized the pawl 91 will move downward causing the ratchet wheel 97 to turn counterclockwise the distance of one tooth thus 125 also turning the shaft 98 an equivalent amount.

The shaft 98 which hereinafter will be termed the drive shaft, is journalled in the side supporting plate 30 and the intermediate supporting plate 79. Fixed to said drive shaft is a gear 101 which meshes with the gear 74 and drives it in synchronism with the type wheels to effect contact between the brushes 71, 72 and 73, as previously explained, at the proper time in the cycle of operation of the type wheels (Figs. 6 135 and 9). Also fixed to the drive shaft 98 is a gear 102 which meshes with a gear 103 fixed to a sleeve 104 rotatably mounted on another sleeve 105 which in turn is rotatably mounted on a shaft 106 journalled in the plates 30 and 79. Fixed to 140 the sleeve 104 is a unit of minute type wheels 107 bearing characters 0 to 9 and fixed to the sleeve 105 is a ten minute type wheel 108 bearing characters 0 to 5. Also rotatably mounted on the shaft are two type wheels 109 and 110. The first 145 mentioned type wheel bears characters from 1 to 12 representing the hours and hereinafter termed the hour wheel, the second mentioned type wheel bears characters A. M. and P. M. and hereinafter termed the meridian wheel. Rotatably mounted 150

on a stud 111 (Fig. 10) fixed to the intermediate supporting plate 79 is a day wheel 112 bearing characters 1 to 31. A month type wheel 113 bearing the characters of every month in the year thereon is fixed to a sleeve 114 mounted rotatably on a shaft 115, said shaft being supported at each end by the supporting plates 30A and 30. Rotatably mounted on the sleeve 114 is a year type wheel 116 having a plurality of yearly date characters thereon.

The type wheels just described are driven in train and locked in train in such a manner that each type wheel both drives and locks its next succeeding type wheel with the exception that the day wheel 112 does not drive or lock the month wheel 113. Provisions are made for manually setting the month wheel which will be explained later. The transfer of rotation from one type wheel to another wherein one type wheel is caused to drive the adjacent type wheel at intermittent periods is produced by the well known Geneva type of construction wherein a series of disks 117a, 117b, 117c, 117d and 117e are fixed either directly to the type wheels 107, 108, 109, 110 and 116 respectively or to the sleeves on which said type wheels are mounted in such a manner that each disk turns with its respective type wheel (Figs. 9, 10 and 11). Fixed either directly to the type wheels 108, 109, 110, 116 or to the sleeves on which they are mounted, in a similar manner to the previously mentioned disks, are gears 118a, 118b, 118c and 118e. These gears 118a, 118b, 118c, and 118e are adjacent to the disks 117a, 117b, 117c, and 117e and coacting with the adjacent members are spur gears 119a, 119b, 119c, 119d and 119e. The mechanism for the transfer from the type wheel 110 to type wheel 112 will be explained in detail later. The disks 117 are all of a similar type having a shoulder 120 cut around the periphery, (Fig. 11) and one or more notches 121 depending on the number of times the disk must transfer during one revolution. This is determined by the kind of type wheel the disk is carried by. For example, the disk illustrated in Fig. 11 bears the reference numeral 117b as it is associated with the tens minute type wheel 108 which as explained bears two sets of characters 0 to 5, 0 to 5. As this wheel effects transfer when it passes from 5 to 0 it will be seen that two transfers will be effected during one revolution of said type wheel and hence this disk requires two notches 121, as shown. The disk associated with the meridian type wheel will require a notch for every two characters A. M. and P. M. on the wheel. The spur gears 119a and 119c are rotatably mounted on the shaft 122 and are held in position by spacing sleeves 123, said shaft being supported by plates 30 and 79. The spur gears 119b and 119d are fixed to the shafts 124 and 125 respectively both shafts being journalled in the plates 30 and 79. The spur gears 119e is rotatably mounted on the shaft 126. These spur gears are all of the Geneva type having every other tooth cut away to a narrower face than its adjacent tooth. Thus the two wide teeth 127 and 127a ride on the periphery of the disk while the narrow tooth 128 meshes with the adjacent gear 118b (Fig. 11) said narrow tooth projecting into the groove formed by the shoulder 120. Adjacent the notch 121 and on each side are projections 129 intercepting the path of the shoulder 120. As the disk 117b revolves the width teeth 127, resting on the periphery prevents the spur gear 119b from turning and therefore no motion is transferred to the gear 118b. When one of the projections 129

strikes the narrow tooth 128, in the path of its travel the wide tooth 127 is in a position to roll into the notch 121 and so the spur gear turns through one wide tooth the next succeeding tooth striking the periphery of the disk and holding the spur gear stationary until another notch is encountered. When the spur gear 119 thus turns it turns the gear 118b coacting with it thus advancing the type wheel fixed to said gear.

The units minute wheel 107 therefore, is advanced periodically by the ratchet wheel 97 and coacting mechanisms previously explained, which transfers one step to the tens minute wheel 108 for each revolution of the units minute wheel. The tens minute wheel 108 transfers two steps to the hour wheel 109 for every revolution, the hour wheel 109 transfers two steps to the meridian wheel 110 for every revolution and the meridian wheel 110 transfers one step to the day wheel 112 for every two steps it is advanced by the hour wheel 109.

The method of transferring from the meridian wheel to the day wheel may be explained by referring to Figs. 5, 6, 9 and 10. A gear 130 is fixed to the shaft 125 to which the spur gear 119d is fixed as previously explained. This gear 130 meshes with a gear 131 fixed to a sleeve 132 rotatably mounted on a shaft 133 said shaft being supported by the plates 79 and 30. Fixed also to the sleeve 132 is a gear 134 which meshes with a gear 135. Said gear 135 is rotatably mounted on a stud 136, said gear and stud being mounted in a cut out portion of a solid disk 137 which is integral with a gear 138 and which is rotatably mounted on the shaft 133. The periphery of the gear 135 extends on each side of said disk 137 meshing with a gear 134 on one side and a gear 139 on the other. The gear 139 is fixed to a sleeve 140 on the opposite end of which is fixed a gear 141. Both last mentioned gears and sleeve are rotatable on the shaft 133. Meshing with the gear 141 is a gear 142 which is fixed to the sleeve on which the day wheel 112 is mounted. It will be noted from Fig. 10 that the day type wheel is cut away in the center so that the gears 141 and 142 lie in the same plane with the type wheel 112. When, therefore, a transfer is initiated through the spur gear 119d said transfer is transmitted to the day wheel 112 through the gear train as follows: gears 130, 131, 134, 136, 139, 141 to gear 142 fixed to the type wheel. Gear 138 remains stationary except when manual setting is required. To effect manual setting a shaft 143 (Fig. 5) is provided with key receiving means 144 at one end extending through the plate 30A in which said shaft is journalled, the other end being journalled in the plate 30. Mounted on a collar 145 fixed to said shaft is a gear 146 which meshes with the gear 138. Fixed also to the shaft 143 is an aligning wheel 147 (Fig. 13). Coacting with the indentations of said aligning wheel is one end of an aligning pawl slidably mounted on a stud 149 fixed to the supporting plate 30a the other end of said pawl coacts with the flat sides of a duplex aligning member 150 fixed to the shaft 140. The purpose of which will be explained later.

Said aligning pawl is biased against the two aligning members by the spring 152 secured at one end to the aligning pawl 148 and at the other end to a stud 153 on the plate 30a. This aligning pawl therefore acts as an impositive stop for the day wheel 112 and also for the month wheel 113. When the shaft 143 is turned by means of a key provided for the purpose the gear 138 is turned by means of the gear 146. The

gear 135 being carried around with the gear 138 in a planetary motion is rotated by being rolled around the periphery of the gear 134 which is now fixed. The gear 139 therefore is driven by the 5 gear 135 in the same direction as the gear 138 and therefore advances the day wheel 112. Thus the provision of a differential in this manner permits the manual setting of the type wheel without disconnecting said type wheel from its 10 normal driving means and without unlocking any of the locking means.

The manual setting of the month wheel 113 is effected by means of a key not shown, which may 15 coact with key receiving means 154 provided on the end of the shaft 126 said shaft being journaled in the supporting plates 80 and 30A (Fig. 10). Fixed to the shaft 126 is a gear 155 meshing with a gear 156 fixed to the month type wheel 113. Turning this shaft 126 therefore rotates the month type wheel and by means of the duplex aligning member 150 and its coacting pawl 148 (Fig. 13) previously explained said type wheel is held impositively in whatever position set. The year type wheel 116 is advanced one step for 20 every revolution of the month type wheel through the disk 117e, gear 118e and spur gear 119e, these being of the same type of transfer mechanism previously described.

Ribbon feed mechanism

An ink ribbon 160 passes under the type wheels in order to effect printing when the type head or printing head is depressed against the platen 21 (Fig. 4). Said ink ribbon is wound on two spools 30 161a and 161b (Figs. 7 and 9). Said spools are provided with holes running laterally through their centers and the holes are provided at each end with bushings 162 having a square hole to cooperate with the square shank 163 of the spindles 33a and 33b, said spindles supporting said spools. The end of the shank 163 is bifurcated one of the bifurcations 164 being formed into a hook shaped member which cooperates with a shoulder in a square hole in the ratchet wheel 45 165b thus forming an impositive catch which holds the spindle in cooperation with the ratchet wheel so that the turning of said ratchet wheel turns its cooperating spindle and with it its associated ribbon spool. The end of the spindle 50 33b opposite the ratchet wheel 165b is journaled in the supporting plate 30. Due to the latch 164 being of an impositive nature the spindle 33b may be withdrawn for removing the spool 161b for replacement of the ink ribbon. A spring 166b 55 fixed to the supporting plate 30 presses against the head of the spool 161b thus preventing the spool from dropping out when the spindle 33b is removed. This is important inasmuch as the spindles have to be withdrawn whenever the side 60 plates 24 and 24a are removed which may be for reasons unrelated to the ribbon spools. The ratchet wheels 165a and 165b are journaled in the supporting plate 30a on one side and in brackets 167a and 167b on the other. These 65 brackets are mounted on studs 168a and 168b fixed to the mounting plate 30a. Friction hubs 169a and 169b are recessed into the holes in these ratchet wheels and are held in under tension of friction springs 170a and 170b also fixed to the studs 168a and 168b, the purpose of which is to prevent any overthrow of travel of the ribbon spools when they are advanced and thus attempt to spin under their own momentum. The spindle 33a, ribbon spool 161a, ratchet wheel 70 165a and parts associated therewith are exactly

the same as the spindle 33b, ribbon spools 161b, ratchet wheel 165b and their associated parts and the description regarding the former just given is equally applicable to the latter.

Means are provided whereby the ink ribbon is moved slightly each time the printing head is depressed in order to present a fresh portion of the ribbon to the type wheels at each printing operation. This is accomplished by means of a lever 57 pivoted at 58 on a turned down portion 56 of the bracket 43. Said lever cooperates with an adjustable limit piece 175 fixed to the base 20. When the printing head of the time stamp is moved downward the right hand end of the lever 57 as viewed in Fig. 4 coacts with the limit piece 175 causing said lever to turn counterclockwise about its pivot 58. The left hand end of the lever 57 is formed over at right angles and cooperates with a lever 176 pivoted at 177 and biased in a clockwise direction as viewed in Fig. 8 by a 95 spring 178 fastened to the lever 176 at one end and to the tie rod 81 at the other end, thus normally supporting the lever 57 in the position shown in Fig. 4. Fixed to the lever 176 is a stud 179 which extends through an enlarged hole 180 100 in the supporting plate 30a. Pivoted to said stud is an irregular shaped member 181 (Fig. 8) the lower projection of which is bifurcated, said bifurcation straddling a stud 182 to prevent the member 181 from swinging about its pivot 179 105 and limit the member 181 therefor to a substantially parallel motion in a vertical direction.

Pivoted to two other projections of the member 181 are ribbon feed pawls 183a and 183b adapted to cooperate with ratchet wheels 165a and 110 165b by a spring 184 attached at one end to the pawl 183a and at the other to a wire 185 which is attached to the pawl 183b (Figs. 5 and 8). With the mechanism in the position as shown in Fig. 8 the ribbon feed pawl 183a is cooperating 115 with the ratchet wheel 165a whereas the ribbon feed pawl 183b is being held out of engagement with the ratchet wheel 165b. When the printing head is depressed the lever 181 moves counterclockwise as viewed in Fig. 8. The stud 179 is 120 therefore moved downward relative to the printing head and with it the regular shaped member 181 carrying the ribbon feed pawls 183a.

The pawl 183a being in engagement with the teeth of the ratchet 165a said ratchet wheel is 125 rotated an amount equivalent to one tooth when said pawl moves downward. When the printing head returns to normal position the pawl 165a is raised and engages the next succeeding tooth the ratchet wheel being prevented from 130 rotating back with the pawl by the friction spring 170a. In this manner the ink ribbon is gradually wound onto the spool 161a. With the pawl 183b engaged with the ratchet wheel 165b the ribbon will be wound on the spool 161b. 135

Ribbon reversing mechanism

Two members 186a and 186b curved to conform with the contour of the ribbon spools are pivoted on shafts 187a and 187b respectively 140 said shafts being supported by the supporting plates 30 and 30a (Figs. 4, 5, and 9). Fixed to these members 186a and 186b opposite and parallel to the shaft on which said members pivot are shafts 188a and 188b on which are pivotally 145 mounted rollers 189a and 189b. One end of the shaft 188a and 188b is extended beyond the mounting plate 30a as shown in Fig. 9. These shafts are connected together by a link 190 (Fig. 8) said link being pivotally mounted at 150

each end of the shafts 189a and 189b. In the center of the link 190 is a projection 191 having an elongated hole through which projects a stud 192 said stud being fixed to a lever 193 pivoted on a stud 194 fixed to the supporting plate 30a. A stud 195 mounted on the lever 193 has fixed thereto one end of a spring 196, the other end of which is fixed to a stud 197 mounted on a V shaped member 198 said member being pivotally mounted on a stud 199 fixed to the supporting plate 30a. The spring 196 is under tension at all times its ends biased in opposite directions with the result the member 198 and the lever 193 are always endeavoring to push each other in opposite directions. The stud 195 on the lever 193 projects through a hole 200 in the supporting plate 30a the sides of said hole coacting with the stud projection to serve as a limit stop for the movement of the lever 193. The lower end of the two legs of the V shaped member 198 are formed at an angle with said member as indicated at 201a and 201b in Fig. 9. These projections coact with the screw heads 82 which serve as limit stops for the movement of the V shaped member 198.

In Fig. 9 the section is taken so as not to show the right hand screw head. Two projections 202a and 202b (Figs. 8 and 9) on the legs of the V shaped member 198 are formed over to intercept and coact with the feed pawls 183a and 183b respectively in a manner such that only one of the pawls at a time is engaged with its respective ratchet wheel. In the position of the mechanism as illustrated in Fig. 8 the lever 193 is at its extreme left hand limit of travel and through the spring 196 the V shaped member 198 is thrown to its extreme right hand limit of travel holding the pawl 183b out of engagement with the ratchet wheel 165b and permitting engagement between pawl 183a and its coacting ratchet wheel 165a. Thus when the feed mechanism operates as previously explained the ribbon will be wound up on the ribbon spool 161b. The stud 192 coacting with the projection in the link 190 will move this link to its extreme left hand limit of travel as viewed in Fig. 8 thus moving the right hand roller 189b to its closest position adjacent the ribbon spool 161b. As the ribbon is wound onto this spool the accumulating layers of ribbon will constantly increase the diameter of the spindle portion of said spool until the diameter increases sufficiently to coact with the roller. As the diameter continues to increase the roller will be forced to the right moving about its pivot 187b and moving the link 190 to the right with it. Lever 193 will be rotated clockwise about its pivot 194 by the link 190 until the stud 195 passes to the right of the stud 197 at which time the opposing action of the spring 196 will swing the V shaped member 198 clockwise about its pivot 199 with a quick shutter like action said member withdrawing the feed pawl 183a from engagement with the ratchet wheel 165a and permitting the engagement of the feed pawl 183b with its coacting ratchet wheel 165b. It will now readily be seen that successive feeding actions of the ribbon feeding mechanism will reverse the direction of the ribbon to wind it on spool 161a, which when full will force the roller 189a to the left to again displace the ribbon feed mechanism until it takes the position as shown in Fig. 8 when the feed of the ribbon is again reversed.

The dial works generally indicated at 205 and 206 previously referred to are driven by a shaft 206

having a worm wheel 207 fixed thereto and meshing with a worm 208 integral with the drive shaft 98, the lower end of the shaft 206 being journalled in a bracket 209 fixed to the intermediate supporting plate 79 (Figs. 4 and 5) and the upper portion of which is journalled in the plate supporting the dial works.

Electrical operation

The manner in which this or a plurality of similar time stamps may be operated by periodic impulses from a primary or master clock and may be corrected if through some external current interruptions the stamps are thrown out of synchronism with the master clock, may best be shown by reference to the wiring diagram in Fig. 14 in which the time stamp magnet 49, the commutators and coacting brushes 71, 72 and 73 are together with the master clock contacts, relay control and associated wiring shown diagrammatically.

The control circuits and master clock switching mechanism are the same as fully described in the patent to J. W. Bryce No. 1,687,491, dated October 16, 1928.

The commutator brushes 71, 72 and 73 on the time stamp are connected to three lines A, B, and C respectively of a three wire circuit running from the control relays and contacts. Lines A and B are the normal impulse transmitting lines and line C being the common return. In the master clock the cams 212, 214 and 216 are rotated by a gear train not shown connected to the time train of the clock. The cams are designed to operate their associated contacts at different timed periods to be explained later. The contact 210 is mounted on the verge of the clock movement, diagrammatically shown, which is oscillated back and forth by the pendulum in the usual manner. With a 60 beat pendulum which is generally used the contact 210 would close every two seconds and therefore are termed hereinafter the rapid impulse contacts. The cam 214 operates its associated contact 213 every minute thereby energizing the relay magnet coil 217 each minute causing its armature to be attracted thus closing the contact 218 every minute. The duration of this closure is approximately one second so that an electric impulse of such a duration is sent out over wire A each minute. Said impulse is likewise transmitted over wire B as long as contacts 219 of the back contact relay 220 are closed. The relay coil 220 is actuated by the closing of contact 215 which is controlled by the cam 216. In the present arrangement the contact 215 closes 44 minutes after the hour and opens 59 minutes and 50 seconds after the hour so that the contact 219 is opened during this period holding the B line out of circuit. The rapid impulse contacts 210 are in series with contact 211 and operate the relay magnet coil 217 when said contacts 211 are closed to transmit these rapid impulses by the rapid operation of the relay contacts 218. The cam 212 is timed to close its associated contact 211 at 59 minutes and 10 seconds after the hour and to open said contact at 59 minutes and 40 seconds after the hour thus transmitting impulses every two seconds as initiated by the closing of contacts 210 for a period of 30 seconds. It will be noted from this timing schedule that the contact 219 is open and therefore the wire B is out of circuit during the transmission of these rapid impulses so that they are transmitted only over the A-wire. The net result of the transmis-

sion of the various impulses over the lines A and B, therefore, is as follows: Minute impulses are transmitted over the A wire each minute of the hour, these minute impulses are also transmitted over the B wire on the even hour and each minute thereafter to the 44th minute after the hour after which the line B is out of circuit or dead until the next 60th minute or even hour. Rapid impulses are transmitted over wire A only for 30 seconds between 59 minutes 10 seconds after the hour and 59 minutes 40 seconds after the hour.

The commutator on the time stamp which is rotated in unison with the minute type wheel is provided with three concentric conducting segments 75, 76, and 77. Segment 75 being annular and continuous, segment 76 extending approximately 90° with the adjacent 270° being an insulated segment, and segment 77 extending approximately 270° with an adjacent insulated segment for the remaining 90°. The driving magnet 49 of the time stamp is connected from line C in series with the brush 73 which wipes on the segment 75. The segments 76 and 77 are wiped by brushes 72 and 71 respectively. The three segments 75, 76 and 77 are electrically connected together so that any impulses flowing over the brushes 71 or 72 that are in contact with either of the conducting segments 75 or 76 will be communicated to the segment 75 and thence through the brush 73 to the magnet 49. The segments are arranged so that the timing of their passage by the brushes ties in properly with the control timing. Brush 71 passes from the conducting segment 77 to its adjacent insulated segment when the time stamp jumps from the 58th to the 59th minute and at the same time the brush 72 passes from the insulated portion to the conducting segment 76, thus disconnecting the stamp from line A and connecting it with line B at that time. The reverse takes place when the time stamp jumps from the 14th to the 15th minute.

If the stamps are all in synchronism with the master no synchronism takes place or is necessary, the magnet 49 receiving regular minute impulses through the A wire and segment 77 until the 59th minute and then through the B wire and segment 76 on the 60th minute.

If any of the time stamps are slow those stamps will have their brushes 71 contact with the segment 73 at the time the rapid impulses are initiated so that such stamps will be stepped ahead rapidly until the brush 71 breaks contact with said segment which will have brought said stamp up to the 59th minute, those stamps that are on time will have already broken contact between the brush 71 and segment 77 and will therefore not receive any of the rapid impulses. Those stamps which are fast will arrive at their 59th minute position before the master clock which will have caused a break in the minute impulse circuit over the A wire by virtue of the brush 71 breaking contact with the segment 77 and thus cause these stamps to stop operation on their 59th minute position. The B line being cut out of circuit no impulses will come through the brush 72 which is in contact with the segment 76 when the stamp reaches its 59th minute position. All stamps having been brought now to the 59th minute position step ahead on the 60th minute as the B line is cut in 10 seconds before the minute impulse for the 60th minute is initiated.

While I have shown and described and pointed out the fundamental novel features of the inven-

tion as applied to a single modification it will be understood that various omissions and substitutions and changes in the form and details of the device illustrated and in its operation may be made by those skilled in the art without departing from the spirit of the invention. I intend to be limited therefore only as indicated by the scope of the following claims.

I claim:

1. In a time stamp, in combination, a base, an arm pivoted on said base having a downward projection, a spring attached at one end to said base, an anchor plate attached to the other end of said spring having an aperture cooperating with said downward projection for raising said arm.

2. In a time stamp, in combination, a base, a spring attached at one end thereto, an anchor plate attached to the other end of said spring, an aperture in said anchor plate, an arm pivoted to said base having a downwardly projecting member projecting through said aperture and means for holding said anchor plate in position to receive said downward projecting member of said arm.

3. In a printing head type time stamp, a printing mechanism, a motor drive mechanism for operating the same, and self synchronizing means for the printing mechanism including a commutator associated with said printing mechanism for controlling the operation of the motor drive mechanism.

4. In a printing head type time stamp, a pivoted arm, a printing mechanism pivoted thereto, a plurality of brush contacts mounted on said printing mechanism, a plurality of releasable contact brush receiving means and means whereby said contact brushes become disengaged from the contact brush receiving means when the printing mechanism is swung forward out of operating position and are reengaged when said printing mechanism is swung back into operating position.

5. In a time stamp, a train of gears for operating type wheels, means for operating the units gear of said train including a reciprocable member having an operating pawl mounted thereon, means for setting the units gear independently of the operating means and means operated by the setting means for automatically disabling the operating pawl during a setting operation.

6. In a time stamp, a train of gears for operating type wheels, means for operating the units gear of said train including a reciprocable member having an operating pawl mounted thereon, means for turning the units gear independently of the operating means to set the same and camming mechanism operated by the turning means during setting operations for camming the operating pawl out of operating position.

7. In a time stamp, a train of gears for operating type wheels, means for operating the units gear of said train including a ratchet operatively connected to said units gear and a reciprocable member carrying an operating pawl coacting with said ratchet means for operating the ratchet independently of its operating pawl to permit setting of the units gear and means operated by the ratchet when moved for a setting operation for automatically removing the operating pawl from coacting relationship with the ratchet.

8. In a time stamp, a train of gears for operating type wheels, means for operating the units gear of said train including a ratchet wheel operatively connected to said units gear and a re-

ciprocable member with an operating pawl pivoted thereon to coact with said ratchet wheel, means independent of the operating pawl for turning said ratchet wheel to effect setting of the units gear and a camming extension on said pawl cooperating with the ratchet wheel to cam the pawl out of operative relationship therewith on a setting operation.

in train, means for operating said type wheels, a ratchet wheel on one of said type wheels adapted to be advanced by said operating means, and means for camming said operating means out of operative relation with said ratchet wheel upon the manual operation of said ratchet wheel.

CLINTON E. LARRABEE.
